UNITED STATES PATENT OFFICE

2,461,644

TOY

Earl C. Hillhouse, Tulsa, Okla.

Application August 14, 1946, Serial No. 690,515

4 Claims. (Cl. 46—130)

1

This invention relates to toys and an object thereof is to provide a toy wherein a movable member including a shaft, carrying figures at its ends, is loosely mounted through a zigzag slot formed in a strip or body, so that when the strip is disposed vertically with the shaft at the upper end of the slot, the shaft will roll downwardly in the slot and cause the figures at ends of the shaft to have movements imparted to them about the axis of the shaft which will be entertaining to children.

Another object of the invention is to provide a toy wherein the elements of the movable member are constructed and arranged to permit adjustment of the figures toward and from the strip or body whereby they may be arranged substantially in balanced relation to cause the movable member to descend rapidly with the axis of the shaft substantially horizontal, and to permit relative adjustment of the figures toward or from the plane of the strip or body whereby they may be arranged in unbalanced relation to cause the movable member to descend slowly and have a wobbling movement as it travels along the slot, if so desired.

Another object of the invention is to provide a toy so formed that the shaft and the roller may be easily fitted into place through the slot but prevented from accidentally slipping out of the slot during use of the toy.

Another object of the invention is to provide a toy having a body or strip which may be set vertically in place upon a table or floor with either end uppermost and reversed after the shaft has moved along the slot to the lower end thereof, and thus again dispose the shaft at the upper end of the body for travel downwardly through the slot.

Another object of the invention is to provide a toy having a body which will be well supported for use, but may be taken apart and packed in a small box when not in use or when initially packed for shipment and storage.

Another object of the invention is to provide a body which may be formed either of wood or sheet material, and manufactured at low cost.

The invention is illustrated in the accompanying drawings wherein:

Fig. 1 is a front elevational view of the improved toy.

Fig. 2 is a side view thereof.

Fig. 3 is a view looking down upon the end piece or support for one end of the body of the toy.

Fig. 4 is an enlarged, fragmentary view, partly

2

in vertical section, and partly in elevation, showing in full lines the balanced position of the shaft of the movable member, and in dotted lines, the unbalanced position thereof.

5 Fig. 5 is a view showing a modified form of the toy, partially in front elevation and partially in vertical section.

Fig. 6 is a side view of the toy shown in Fig. 5.

Fig. 7 is a view in side elevation showing the 10 end piece at the upper end of the toy detached from a fragment of the upper portion of the strip or body of the toy shown in Figs. 5 and 6.

Fig. 8 is a view similar to Fig. 4, showing in full 15 lines, the shaft of the movable member of this modified form of toy, in a balanced position, and by dotted lines, the unbalanced position thereof.

Fig. 9 is a plan view looking down upon an end 20 piece of the modified form.

Fig. 10 is a plan view of the blank from which 25 the metal end piece shown in Fig. 9 is formed.

This toy consists briefly of a body adapted to be supported in an upright or vertical position and formed with a longitudinally extending zigzag slot through which passes a shaft carrying at 30 its ends figures which have movements imparted to them about the shaft as the shaft moves downwardly through the slot.

The toy may be formed mainly of wood or similar material, as shown in Figs. 1 through 4, and 35 in this embodiment of the invention the body 1 consists of a strip of wood of appropriate length and width and having its ends cut straight across at right angles to its side edges. A slot 2 extends longitudinally of the strip or body 1, and upon referring to Fig. 2 it will be seen that this 40 slot is a zigzag slot and at the intersections of its diagonally extending sections 3 is formed with arcuate edges 4 so that during use of the toy a roller 5 may easily move downwardly along the slot from one section 3 thereof to another. A narrow slit 5' is formed longitudinally of the body 45 from one end thereof to the adjacent end portion of the slot 2, this slit being formed during manufacture of the toy by use of a scroll saw used in producing the zigzag slot. This slit 5' also allows the separated portions 6 of the slit 50 end portion of the strip or body to be sprung away from each other for insertion of the roller 5 through the slot.

55 The roller is formed as shown in Fig. 4 and consists of a tubular sleeve 7 having circumferentially extending flanges 8 at its ends, and attention is called to the fact that the length of the sleeve is such that when the roller is passed into the slot 2 it will project from opposite sides of the

body a sufficient distance to allow the roller to be tilted in either direction as shown by dotted lines in Figure 4. The shaft 9 is formed from a dowel of such diameter that it will fit snugly in the bore of the roller and is of such length that when it is passed through the roller it will project a considerable distance from each end of the roller.

Acrobatic figures 10 are carried by end portions of the shaft 9 and as the roller 5 moves along the slot, from the upper end thereof towards its lower end, the shaft turns with the roller and the figures will be moved about the shaft and execute turning movements.

In the present illustration, each figure 10 represents an acrobat having its arms and legs 11 and 12 respectively, pivoted to a body 13 and outer ends of the arms reduced to form pins 14 which are fitted into openings 15 formed through end portions of the shaft. Therefore the figures may be firmly fixed to the shaft, and also easily removed when the toy is to be taken apart and put away in a box.

End pieces 16, which serve as supports for the body or strip 1, are applied to the strip and project from opposite sides thereof. Each end piece is conveniently formed from a wooden block, which may be reduced in thickness towards its ends, and midway its length is formed with a groove 17 to receive the cooperating end of the body. By this arrangement the body 1 may be detachably connected to the pieces 16, and the end piece that is lowermost projects laterally of the body 1, a sufficient distance to cause the body to be supported in an upright position. This is clearly shown in Fig. 1 and referring to this figure it will be seen that the body may be supported upright with either end uppermost. Therefore, after the roller 5, and parts carried thereby, has moved downwardly in the slot to the lower end thereof, the body may be inverted and the movable member will again travel downwardly to the lower end of the slot. As the roller travels downwardly in the slot, it rides upon lower edges of the portions 3 thereof, and since these portions slope in opposite directions, the roller and parts carried thereby will turn first in one direction and then in an opposite direction, during this downward movement and cause the figures to alternate the direction of their movement about the axis of the shaft. By adjusting the position of the shaft 9 through the roller 5 so that it, and the acrobatic figures 10 are in balanced relation with respect to the roller, the movable member will descend rapidly and not wobble, but if in unbalanced relation, it will descend more slowly, and the flanges 8 rubbing on the body 1 will cause it to wobble.

In Figs. 5 through 10, there is shown the modified form of construction which may be formed chiefly of metal. In this embodiment of the invention a body 18 is formed from an elongated blank or strip of tin or other suitable sheet metal. The metal strip has side edge portions bent to form tubular beads or columns 19 and adjacent its ends the metal strip is crimped to form transversely extending reinforcing ribs 20. Slits 21, which are cut along inner sides of the ends of the columns 19, provide tongues 22, which extend the full width of the body between the columns at the ends of the body.

End pieces 23 are provided for support of the body 18, and they are of duplicate construction, each being preferably formed from a sheet metal blank or strip 24, shown in Fig. 10. This blank

is preferably formed with transversely extending rows of perforations 25 and 26 which serve as fold lines and allow the blank to be easily and accurately bent to form each end piece with a flat base 27 from opposite sides of which extend leaves 28 terminating in upstanding lips or tongues 29. Portions of the tongues 29 at opposite sides of the end piece are bowed transversely and cooperate with each other to form sleeves 31 at ends of the tongues 29. When the end pieces are applied to the body 18 the sleeves 31 are fitted into ends of the tubular columns 19, the tongues 22 of the body are fitted between the tongues 29 of the end pieces and the ends of lips or tongues 29 are accommodated in the slits 21.

A shaft 32 of the movable member carries figures 33 and the shaft passes through a roller 34 corresponding to the roller 5. This roller 34 has annular flanges 35 at the ends of its sleeve 36, and when this roller is mounted in a zigzag slot 37 formed in the body 18, the roller will roll downwardly in the slot, and alternately turn in opposite directions during its downward movement.

In this form of the invention, the shaft 32 may be in fixed relation to the roller 34, and the figures 33 slidably secured by frictional engagement on the end portions of the shaft as by use of hubs 38 formed integral with the figures. Thus the figures 33 may be removed for packing and storage, and may be adjusted longitudinally of the shaft 32 for balancing the movable member in the slot 37, or, as shown by dotted lines in Fig. 8, one of the figures 33 may be moved closer to the roller 34 than the other figure to obtain unbalanced relationship and thereby cause the movable member to wobble as it descends with respect to the body 1.

The flanges 35 of the roller 34 are spaced apart a distance greater than the thickness of body 18, so that this wobbling of the movable member may be accomplished and also so that the roller 34 may be placed in the zigzag slot 37, as by springing a tongue like portion 39 of the body 18 between runs 40 of the slot 37 outwardly a distance sufficient to permit a person to cant the roller into place, after which the tongue 39 will spring back to normal position. This enables me to fix the roller 34 to the shaft 32 at the time of manufacture and when placing the roller into the zigzag slot, it is understood that a portion of the shaft 32 is first extended thru the slot at a time when the figure 33 at that portion of the shaft is removed therefrom. Also when removing the roller and shaft from the slot, at least one of the figures must first be removed from the shaft.

I claim:

1. In a toy, an upright body member provided with a zigzag slot extending from an upper portion to a lower portion thereof; and a movable member adapted to descend by gravity with respect to the body member, comprising, a shaft extending transversely thru and revoluble in said slot, an annular flange on said shaft on each side of said slot, said flanges being spaced apart a distance slightly greater than the thickness of said body member, and an acrobatic figure on each end portion of said shaft member, the said elements of the movable member being constructed and arranged to permit relative adjustment of the figures toward and from the plane of the body member whereby they may be arranged substantially in balanced relation to cause the movable

member to descend rapidly with the axis of the shaft substantially horizontal, and to permit of relative adjustment of the figures toward and from the plane of the body member whereby they may be arranged in unbalanced relation to cause the movable member to descend slowly with the peripheries of the flanges rubbing against the upright member and the axis of the shaft extending diagonally with respect to the plane of the body member.

2. In a toy, an upright body member provided with a zigzag slot extending from an upper portion to a lower portion thereof; and a movable member adapted to descend by gravity with respect to the body member, comprising a roller, provided with an axial bore, revoluble in said slot, a flange carried by each end portion of the roller, said flanges disposed at opposite sides of the body member and spaced apart a distance slightly greater than the thickness of said body member, a shaft extending thru said bore and having snug frictional engagement with the roller, and an acrobatic figure on each end portion of the shaft, said shaft being adjustable longitudinally in said bore whereby the figures may be arranged in balanced relation to cause the movable member to descend rapidly with the axis of the shaft substantially horizontal, and to permit adjustment of the shaft with one of the figures to a position nearer the plane of the body member than the other figure, whereby they may be arranged in unbalanced relation to cause the movable member to descend slowly with the peripheries of the flanges rubbing against the upright member and the axis of the shaft extending diagonally with respect to the plane of the body member.

3. In a toy, an upright body member provided with a zigzag slot extending from an upper portion to a lower portion thereof; and a movable member adapted to descend by gravity with respect to the body member, comprising a roller revolvable in said slot, a flange at each end portion of the roller, said flanges disposed at opposite sides of the body member and spaced apart a distance slightly greater than the thickness of said body member, a shaft carried by and coaxial with said roller and extending outwardly beyond said flanges and an acrobatic figure on each end portion of said shaft, said figures each having a hub in snug frictional engagement with its re-

spective end portion of the shaft whereby the figures may be adjusted longitudinally of the shaft to substantially balanced relation to cause the movable member to descend rapidly with the axis of the shaft substantially horizontal, and to permit adjustment of one of the figures on the shaft to a position nearer the plane of the body member than the other figure, whereby they may be arranged in unbalanced relation to cause the movable member to descend slowly with the peripheries of the flanges rubbing against the upright member and the axis of the shaft extending diagonally with respect to the plane of the body member.

4. A toy comprising a body formed from a strip of sheet metal having side edge portions rolled to form tubular columns along opposite side edges of the body, said body being formed with a longitudinally extending zigzag slot, base members detachably engaged with the ends of the body for reversibly supporting the body upright, said base members each consisting of a sheet of metal provided with fold lines and bent along the fold lines to form a bottom plate and leaves extending inwardly over the bottom plate from opposite ends thereof and terminating at their free ends in upwardly projecting lips constituting jaws, the said jaws having their ends bowed transversely and cooperating to form sleeves at opposite ends of the jaws, said sleeves fitting snugly in the ends of the columns and end portions of the body between the columns being gripped between the jaws of the base member, a shaft passing thru the slot and mounted for rolling movement downwardly in the slot, and figures carried by ends of the shaft.
